Gowett and Little of Crescent, N. Y.
Letters Patent No. 828. Dated August 26th 1856.

The schedule referred to in this Letters Patent, and making part of the same.

To all whom it may concern:

Be it known that we, N. G. Nodder and Mr L. Sandusow, each of the City of Troy, in the County of Rensselaer, and State of New York, have jointly invented or produced a new and original design for the Front and Side Plates of a Cooking Stove, which we call "La Belle"; and we do hereby declare that the following is a full and exact description of the same, reference being had to the annexed drawings, making a part of this specification, in which Fig. 1, is an elevation of the front plate; Fig. 2, a section of the front plate at the line w, y, in Fig. 1; Fig. 3, an elevation of the side plate; and Fig. 4, a section of the side plate at the line y, z, in Fig. 3; - The same letters refer to like parts in all the figures.

A, A', are the upper, and B, B', the lower doors of the front plate; and C, is the feed door, and D, the small, and E, the large oven door of the side plate.

The ornaments of the front plate consist of the plain columnar mouldings F, F', at the ends of the plate; - the bead mouldings a, a', surrounding the panel ornaments of the doors A, A', which ornaments consist of the zigzag work b, crescents c, hemisphere d, recessed moulds e, and the variously formed connected pyramids f, g, h, - all shaped and arranged together as shown in Fig 1; - and of the compound mouldings i, surrounding the panel ornaments of the doors B, B', the ornaments of which, each consist of the serpentine work j, crescents c', zigzag work k, oval and recessed parts l, e', arrowheads l', pyramids m, and the connected pyramids f', g', h', all formed and arranged together as shown in the drawings.

The design of the said plate consists of the broad compound mouldings H, I, at the top and bottom; - the compound moulding m, surrounding the panel ornaments on the door F; which ornaments consist of the raised recessed parts p, which support the connected pyramids f, g, h, the crescents c², with a stave, within each, - the oval and recessed parts d², e², serpentine work j', zigzag work n, and the compound arrowhead s, all shaped and arranged together as shown; - the compound moulding

t, around the panel ornaments of the door D, - which ornaments consist of the raised parts w , supporting the pyramids w , and crescents c , the supertine work j ; - zigzag work r ; arrowheads s ; and the central parts d , e ; all shaped and arranged as shown; - and of the compound molding v, around the panel ornaments of the door C, which ornaments are composed of the central parts d , e , raised parts w , which support the pyramids w , and crescents c ; the supertine work j ; zigzag work r ; and arrowheads s ; all formed and arranged together as represented in the drawings.

What we claim and desire to secure by letters patent is, the ornamental design herein described and represented in the annexed drawings, for the front and side plates of a cooking stove.
